UNITED STATES PATENT OFFICE

ALOIS L. MARTINEK, OF DETROIT, MICHIGAN, ASSIGNOR TO C. M. HALL LAMP COMPANY, OF DETROIT, MICHIGAN, A CORPORATION OF MICHIGAN

LAMP

Application filed May 26, 1930. Serial No. 455,866.

This invention relates generally to lamp constructions and consists of certain novel features of construction, combinations and arrangements of parts, that will be hereinafter more fully described and particularly pointed out in the appended claims.

Heretofore the bulb sockets of certain lamps have been mounted in or carried by the reflectors or associated parts of the lamps and difficulty has been experienced in properly mounting the sockets in this manner. Moreover, special bushings or other parts have been needed to accomplish the mounting and the cost of installing such parts has been quite an item. It is also customary in certain lamp constructions to press inwardly an annular portion of the lamp body at the free edge thereof to provide a seat for the door of the lamp. When the body has a rounded outer surface and is relatively shallow it is difficult to center the body in a jig so that the annular seat may be accurately formed. As a consequence I have provided an opening in the body at the center thereof to receive a centering pin so that the body may be centered in a jig and the seat may be accurately formed. I have also utilized this opening as a means for receiving a securing means for the lamp so that the latter may be conveniently secured directly to the body of the lamp at the axis thereof. In fact, the securing means is such that it conceals the opening and provides a neat appearance.

In the accompanying drawings:

Figure 1 is a vertical sectional view through a slightly modified construction;

Figure 2 is a perspective view of the door and yoke;

Figure 3 is a sectional view taken on the line 3-3 of Figure 1.

Referring now to the drawings, the rivet 20 used for securing the socket 21 to the body 22 at the axis of the latter is hollow and receives a screw 23 that threadedly engages the base 24 of a yoke 25 for securing the door 26 in closed position upon the body. As shown, the rivet 20 extends through aligned openings 27 and 28 respectively in the socket flange 29 and body 22 and has lateral flanges 30 and 31 respectively overlapping portions

of the flange 29 and body 22. The screw head 32 virtually conceals the flange 31 so that a neat appearance is provided. The yoke 25 may be any suitable construction but preferably comprises a narrow strip of metal bent 55 into substantially U form with the end portions 33 and 34 respectively turned outwardly and engaging beneath the inturned marginal flange 35 of the door. Pins 36 project laterally from the arms 37 and 38 respectively 60 of the U adjacent the flange 35, and springs 39 and 40 respectively extend between the reflector flange 41 and pins and yieldingly hold the reflector 42 upon the door and hold the end portions 33 and 34 of the yoke in engagement with the marginal flange 35. Thus in this construction the rivet 20 serves the added function of a sleeve for the door securing means.

What I claim as my invention is:

1. In a lamp, a lamp body, a lamp bulb socket at the center of the body, a hollow rivet extending through the center of the body and socket and having flanges overlapping said parts whereby the socket is secured directly to the body, a removable door for the body, a reflector concavo-convex in shape having a marginal flange rigid with the door and provided at its center with an opening that receives the socket when the door is closed and is of sufficient size to receive a bulb in the socket when the door is moved to and from the body, and securing means for the door including a yoke, and a screw extending through the rivet and threadedly engaging the yoke.

2. In a lamp, a lamp body, a lamp bulb socket having a portion adjacent a portion of the body, a hollow rivet extending through the adjacent portions of the body and socket and having flanges overlapping said portions whereby the socket is secured directly to the body, a removable door for the body, a reflector carried by the door and provided with an opening that receives the socket when the door is closed and is of sufficient size to receive a bulb in the socket when the door is moved to and from the body, and securing means for the door including a yoke project-

ing rearwardly from the door, and a screw extending through the rivet and yoke.

3. In a lamp, a lamp body, a lamp bulb socket having a portion adjacent a portion of the body, a hollow rivet extending through the adjacent portions of the body and socket and having flanges overlapping said portions whereby the socket is secured directly to the body, a removable door for the body, and securing means for the door including a yoke projecting rearwardly from the door, and an element fastening the yoke to the rivet aforesaid, and accessible from the outside of the body.

15 4. In a lamp, a lamp body, a lamp bulb socket having a portion adjacent a portion of the body, a hollow rivet extending through the adjacent portions of the body and socket, and having flanges overlapping said portions 20 whereby the socket is secured directly to the body, a removable door for the body, a reflector having a marginal flange connected to the door and having an opening receiving the socket, and securing means for the door 25 including a yoke projecting rearwardly from the door, and an adjustable element extending through the yoke and mounted for rotary movement within the hollow rivet aforesaid.

In testimony whereof I affix my signature.
50 ALOIS L. MARTINEK.
